UNITED STATES PATENT OFFICE.

WILLIAM McCONWAY, JR., OF PITTSBURGH, PENNSYLVANIA, ASSIGNOR TO McCONWAY & TORLEY COMPANY, OF PITTSBURGH, PENNSYLVANIA, A CORPORATION OF PENNSYLVANIA.

CAR-COUPING.

1,148,027.

Specification of Letters Patent. Patented July 27, 1915.

Application filed March 18, 1914. Serial No. 825,655.

To all whom it may concern:

Be it known that I, WILLIAM McCONWAY, Jr., a citizen of the United States, residing at Pittsburgh, in the county of Allegheny and State of Pennsylvania, have invented certain new and useful Improvements in Car-Couplers; and I do hereby declare the following to be a full, clear, and exact description of the invention, such as will enable others skilled in the art to which it appertains to make and use the same.

My invention relates to the construction of pivotally mounted couplers for connecting railway vehicles to each other, and is especially applicable to tender couplers though not limited thereto.

The principal objects of the invention are to provide simple and efficient means for preventing drooping of the coupler head and for conveniently and readily adjusting the coupler vertically to compensate for the sagging of springs, wear of the wheels and other similar results of service affecting the height of the coupler head above the rails.

Generally stated, these objects are accomplished by providing a coupler pocket and pivotally connecting the shank of a coupler thereto in such manner that the latter is capable of swinging laterally to the desired extent, one of said members being provided with slots or recesses and the other of said members being provided with flanges which are adapted to enter said slots to thereby maintain the coupler in a plurality of positions of vertical adjustment above the track rails.

In the drawings chosen for the purpose of illustrating my invention, the scope whereof is pointed out in the claims, Figure 1 is a plan view of a tender coupler embodying my invention. Fig. 2 is a view showing the pocket member of the coupler in horizontal section on the line 2-2, Fig. 3, and illustrating the coupler in plan in one of its extreme laterally displaced positions. Fig. 3 is a side elevation of the coupler, the parts being in the relative positions illustrated in Fig. 1; and Fig. 4 is a detail view illustrating the manner of assembling the coupler in the coupler pocket.

In the drawings, 1 indicates the coupler and 2 is the coupler pocket or member by which the coupler is attached to the tender or other railway vehicle. These two mem-

bers are preferably pivotally connected by means of a pivot pin 3 which passes through an aperture near the rear end of the coupler-shank and through corresponding apertures near the inner end of the flaring recess of the pocket member into which such coupler shank extends. The rear end of the coupler shank may be formed, if desired, with cylindrical bearing faces 4 which are concentric with the pivot pin opening in the coupler shank and which are adapted to transmit the force of buffing shocks to the correspondingly curved bearing faces 5 upon the interior of the pocket member 2.

Projecting laterally from the sides of the coupler shank, and preferably located midway between the top and bottom faces thereof, are horizontally extending flanges 6 which are of less height than the coupler shank and which are adapted to enter appropriately formed corresponding slots or recesses 7 with which the pocket member 2 is provided. These flanges 6 are preferably of generally triangular form, as more particularly shown in Fig. 2, diminishing in width toward the rear end of the coupler shank. By so forming the flanges 6 the pocket member 2 may be made of comparatively small dimensions and correspondingly light in weight, while yet serving to permit an extended lateral swinging of the coupler 1 and to simultaneously engage the flanges 6 on both sides of the coupler shank, thereby insuring effective vertical support to the coupler throughout its entire arc of lateral displacement.

As a further means for preventing drooping of the head of the coupler 1, the rear end of the shank of the coupler is preferably formed with a rearwardly extending projection 8 which may be conveniently located in the plane of the supporting flanges 6 projecting laterally from the sides of the coupler shank. This projection or flange 8, which is of less height than that of the coupler shank, is adapted to enter and move with the coupler in either of the corresponding slots or recesses 9 formed in the base of the pocket member 2.

When the device is in service the laterally projecting flanges 6 of the coupler shank engage and are supported by the lower faces or floors of the particular slots 7 into which the said flanges 6 may have

been inserted in assembling the parts, while the rearwardly extending projection 8 at the end of the coupler shank engages the upper face or wall of the appropriate slot 9, means being thus provided both in advance 5 and to the rear of the pivot pin 3 for preventing the drooping of the coupler.

For convenience of effecting temporary repairs while on the road, the coupler 10 pocket is, as shown, preferably formed with a flaring pocket so as to be capable of receiving any of the generally employed forms of pivoted couplers and the usual form of shims commonly adopted for adjusting the height of the coupler above the rails.

I claim:

1. In a device of the character indicated, the combination with a pocket member, of 20 a coupler which is pivotally supported by said pocket member, means connected to said coupler and located in advance of the point of pivotal connection of the pocket member and coupler for preventing drooping of 25 said coupler, and means to the rear of the said point of pivotal connection for preventing drooping of said coupler.

2. In a device of the character indicated, the combination with a pocket member, of 30 a coupler adapted to be pivotally connected thereto in a plurality of positions of vertical adjustment, and means located to the rear of the point of pivotal connection of the pocket member and coupler for preventing 35 drooping of said coupler, the same means serving to prevent drooping of the coupler in either of its said positions of vertical adjustment.

3. In a device of the character indicated, 40 the combination with a pocket member, of a coupler pivotally connected thereto, said coupler being provided to the rear of its said point of pivotal connection with a projection, and said pocket member being provided with a plurality of slots each of which 45 is adapted to receive said projection.

4. In a device of the character indicated, the combination with a pocket member, of 50 a coupler pivotally connected thereto, said coupler being provided with oppositely extending flanges, and said pocket member being provided with slots adapted to receive the corresponding flanges.

5. In a device of the character indicated, 55 the combination with a pocket member, of a coupler pivotally connected thereto, said pocket member being provided with a plurality of slots, and said coupler being provided with oppositely extending flanges 60 which are adapted to enter the corresponding slots of the pocket member to thereby vertically adjust the said coupler with respect to said pocket member.

6. In a device of the character indicated, 65 the combination with a pocket member, of a

coupler pivotally connected thereto, said pocket member being provided with a plurality of slots, and the shank of said coupler being provided with a plurality of laterally extending flanges which are wider at some 70 points than at others and which are adapted to enter the corresponding slots of said pocket member.

7. In a device of the character indicated, the combination with means for supporting 75 a coupler upon a railway vehicle, of a coupler having means whereby it may be pivotally connected to said supporting means and having a shank which is provided with a plurality of oppositely extending projections that are adapted to overlap said supporting means.

8. In a device of the character indicated, the combination with means for supporting a coupler upon a railway vehicle, of a coupler having means whereby it may be connected to said supporting means and having a shank which is provided with laterally extending projections that are of less height 85 than the height of the shank and that are 90 adapted to overlap said supporting means.

9. In a device of the character indicated, the combination with a pocket member, of a coupler pivotally connected thereto and adapted to be assembled therewith in a plurality of positions of vertical adjustment, 95 said pocket member and the rear end of said coupler being provided with interfitting means adapted to restrain vertical movement of the rear end of said coupler in its 100 several positions of vertical adjustment.

10. In a device of the character indicated, the combination with a pocket member, of a coupler having a pivot pin opening in the shank thereof and provided to the rear of 105 said opening with a horizontally extending projection of less height than the shank of said coupler and provided in advance of said opening and extending to the rear of the head of the coupler with a plurality of 110 laterally extending flanges, said horizontally extending projection and said laterally extending flanges engaging said pocket member.

11. A coupler pocket provided with means 115 whereby a car coupler may be pivotally connected thereto, and having a flaring recess and being provided with a plurality of slots communicating with said flaring recess at the opposite sides thereof.

12. A coupler pocket provided with a pivot pin opening whereby a car coupler may be pivotally connected thereto, and having a flaring recess and being provided to the rear of said pivot pin opening with a plurality of slots communicating with 125 said flaring recess.

13. A coupler pocket provided with pivot pin openings whereby a car coupler may be pivotally connected thereto, and having a 130

flaring recess and being provided with a plurality of slots communicating with said flaring recess at opposite sides thereof and in advance of said pivot pin openings, and
5 being further provided with a plurality of slots communicating with said flaring recess to the rear of said pivot pin openings.

In testimony whereof I affix my signature, in the presence of two subscribing witnesses.

WILLIAM McCONWAY, Jr.
